UNITED STATES PATENT OFFICE.

THOMAS E. JORDAN, OF BEVERLY, MASSACHUSETTS, ASSIGNOR, BY MESNE ASSIGNMENTS, TO THE JIFFY BRUSH COMPANY, A CORPORATION OF MASSACHUSETTS.

RESERVOIR-BRUSH.

1,197,210.

Specification of Letters Patent. Patented Sept. 5, 1916.

Application filed June 14, 1915. Serial No. 33,922.

To all whom it may concern:

Be it known that I, THOMAS E. JORDAN, a citizen of the United States, residing at Beverly, in the county of Essex and State 5 of Massachusetts, have invented a certain new and useful Improvement in Reservoir-Brushes, of which the following is a full, clear, and exact description, reference being had to the accompanying drawings.

10 This invention relates to brushes having provision therein for holding a supply of plastic or viscous material together with means for extruding the same into the brush as desired for use. For purposes of illustration herein I have shown a shaving brush 15 equipped with a reservoir adapted to be filled with soap of suitable nature for shaving, though it is obvious that brushes of many kinds could be equipped in this manner such as glue brushes, marking brushes, etc.

20 The object of the invention is the provision of a reservoir brush adapted to receive and coöperate with containers of a well known commercial type; while further objects and advantages of the invention will become apparent as the description proceeds.

Generally speaking my invention may be 25 defined as consisting of the combinations and constructions recited in the claims here-to annexed and illustrated in certain embodiments in the drawings accompanying and forming a part of this application, 30 wherein:

Figure 1 is a perspective view of a complete brush constructed in accordance with my invention; Fig. 2 is a longitudinal sectional view through the center of such a brush; Fig. 3 is a perspective view of the soap container or reservoir before application to the brush; Fig. 4 is a perspective view of the removable bottom washer; Fig. 5 is a longitudinal sectional view through 35 my improved brush showing a modified form of soap container; Fig. 6 is a perspective view of said soap container partially full of soap and before application to the brush handle, a portion of the side wall 40 being broken away; and Fig. 7 is a longitudinal sectional view of another form of my invention.

Describing the parts by reference characters, my improved brush comprises a low cylindrical handle 1 formed with an

interior thread 2, preferably of a left-hand nature, and preferably having one end closed as at 3. To the other end of the handle is affixed a brush base 4, here shown as a hollow ferrule and secured, in the present 50 instance, by means of a threaded gland 5, sufficient play being left so that the ferrule may be rotated about its longitudinal axis. The outer end of the ferrule is preferably slightly tapered as shown at 6, and receives 55 the bristles 7, the same being secured in place in any suitable or convenient manner. Inside of this brush base is rigidly mounted a central axial discharge duct 8 whose end projects into the middle of the brush. At 60 its rearward end I have shown the duct 8 as formed with an enlarged internally threaded socket 9 adapted for connection to the soap reservoir hereafter described. This soap reservoir consists of a hollow collapsible tube, but its exact shape and method of use may take any one of several different forms. In the form shown in Figs. 2 and 3 65 this reservoir consists of a cylindrical collapsible tube 12 formed of any suitable material, but preferably of the same lead-and-tin combination so widely used for that purpose. The forward end of the tube is provided with a threaded nipple 13 adapted to be attached to the socket 9 as shown 70 in Fig. 2, but before such attachment being closed by the screw cap 14. The opposite end of the tube is drawn together and secured in a single flat seam or fold. Preferably the sides of the tube are creased in 75 inwardly as shown at 16 so that the length of this fold may not be greater than the diameter of the tube, and the fold is preferably stiffened by means of a U-shaped clip 17 80 rigidly affixed thereto.

Located within the handle 1 and meshing with the threads thereof is a movable piston 20 having its forward face formed with a narrow slot 21 adapted to receive the folded tube-end 17. With this construction it will 85 be seen that the rotation of the handle 1 will cause the piston 20 to advance toward the brush, telescoping and crumpling the collapsible tube and ejecting the material therein 90 out through the duct 8. Ordinarily the rotation of the piston 20 will be prevented by the rigidity of the tube walls, particularly 95 considering that while they are smooth the tube contents will afford them considerable 100 rigidity, and that as soon as they have be- 105 110

come crumpled this very fact will add greatly to their resistance. However even if the piston should follow the movement of the handle and so twist the tube the result 5 would be to decrease the capacity of the tube and eject its contents.

In Figs. 5 and 6 I have illustrated a modified form of container in which a pair of rigid end members 13^a and 17^a, respectively, 10 are connected by a fabric or other flexible wall 24 securely affixed thereto in any suitable manner as by constricting wires 25, 25. In this embodiment I have illustrated the 15 end members as connected together by the helical spring 26 which prevents their relative rotation while permitting them to approach each other. In this embodiment I have shown the threaded piston 20^a as integrally connected with the end member 17^a 20 instead of detachable therefrom as in Figs. 2 and 4.

In the embodiment illustrated in Fig. 7 the handle 1^a is interiorly smooth and provided at its closed end with a gripping member 30 adapted to receive the closed end of a soap tube inserted therein, so that when the two parts of the brush are turned relatively to each other this tube is twisted and the contents thus ejected.

It will be obvious that a great many changes 25 in addition to those described could be made

without departing from the scope of my invention, wherefore I do not limit myself to the details herein described except as specifically recited in the claims or rendered necessary by the prior art.

Having thus described my invention, what I claim is:—

1. The combination of a base having a discharge duct therein, adapted to receive the neck of a collapsible tube, a hollow handle 40 for inclosing the tube, a coupling between the front end of the tube and the base, permitting relative rotation thereof, and means in the handle for collapsing the 45 tube when said handle is rotated.

2. In a device of the character described, a brush base, a hollow handle swiveled thereto, a discharge duct carried by said brush base and adapted to receive the discharge 50 neck of a collapsible tube, and slotted means in said handle adapted to receive the closed end of said tube, said means being arranged to be moved relatively to said brush base 55 upon the rotation of said handle.

In testimony whereof, I hereunto affix my signature in the presence of two witnesses.

THOMAS E. JORDAN.
